UNITED STATES PATENT OFFICE

2,556,107

LIQUID HEATING SYSTEM

Charles Neil Roswell, Chicago, Ill.

Application February 17, 1948, Serial No. 8,849

11 Claims. (Cl. 257—24)

1

This invention relates to an improved heat exchanger and controls therefor for heating flowing liquids to any desired temperature and automatically maintaining the temperature of the heated liquid substantially constant.

In my copending application, Serial No. 737,676, filed March 27, 1947, now Patent No. 2,533,141, I have disclosed and claimed a liquid heating system wherein means are provided for automatically controlling the flow of liquid being heated, for automatically maintaining the temperature of the liquid substantially constant and for removing the condensate from the heater at a controlled rate. Systems of this type are particularly useful for heating food products such as milk, fruit juices, and the like where very close control must be maintained, but it is believed obvious that any liquid may be heated in such a system. The present heat exchanger is an improvement over that disclosed in the copending application in that the condensate removal means is now a compact unit occupying a minimum of space and is arranged to operate in a more simple manner. In the present invention the heating chamber is provided with removable headers and each header is sealed by means of an inexpensive disposable paper gasket.

The primary object of the present invention is to provide a liquid heating system employing steam as the heating medium in conjunction with means for removing condensate including a condensate chamber communicating directly with a steam chamber, a pump having its intake communicating with the condensate chamber, an outlet from the pump, and means for recirculating a portion of the condensate from the outlet conduit through said pump.

A further object of the invention is to provide such a liquid heating system wherein the outlet from the pump communicates with a Venturi ejector having a gas line extending between the ejector and the condensate chamber for removing non-condensable gases, and means for preventing escape of condensate from the system when the gases are vented.

Another object of the invention is to provide means for ejecting condensate to the sewer or the like comprising a valve in an outlet line from the pump with this valve being operated by a float in the condensate chamber so that a relatively constant level is maintained in the condensate chamber and thus a relatively constant head is maintained on the pump.

A still further object of the invention is to provide such a condensate ejecting system wherein the float operated valve is located in the condensate chamber with fluid-tight passages being provided to and from the valve for permitting access thereto.

Another object of the invention is to provide

2

such a system wherein the Venturi ejector that is used for the removal of non-condensable gases is maintained submerged in a substantially constant head of condensate in order that the ejector will operate with high efficiency.

A still further object of the invention is the provision of a steam chamber or the like having a removable header thereon and a disposable gasket of paper serving to seal the header on the chamber.

Other objects and advantages of the invention will become apparent in the following description of one embodiment of the same taken in conjunction with the accompanying drawings. Of

15 the drawings:

Fig. 1 is an elevation of one embodiment of the invention with a portion broken away for clarity of illustration; Fig. 2 is an enlarged sectional elevation of the apparatus of Fig. 1 illustrating the means for withdrawing steam condensate and non-condensable gases; and Fig. 3 is an enlarged fragmentary elevation of a portion of a header, gasket and the adjacent portion of the steam chamber.

25 In the embodiment shown in the drawings, there is provided a heat exchanger 10 formed with an expansion ring 16a near one end thereof, a centrifugal pump 11 for pumping liquids through the exchanger, a steam supply line 12 to the exchanger, a steam supply valve 14 in the steam line 12 for regulating the amount of steam, a thermostatically operated temperature control pilot valve 15 for controlling the operation of the valve 14 from the temperature of the 30 heated liquid, a steam condensate chamber 16 located below the heat exchanger 10 and communicating therewith, a second centrifugal pump 17 for drawing condensate from the condensate chamber 16, a float operated valve 18 through which the pump 17 exhausts condensate, a Venturi ejector 19 through which condensate is forced by the pump 17, and a housing 20 around the Venturi ejector 19 adapted to contain condensate at a substantially constant level and 35 pressure.

40 The heat exchanger 10 is provided with a plurality of substantially parallel pipes 21 extending from end to end thereof and a pair of headers 22 and 23 at the ends of the heat exchanger partitioned so that the liquid being heated may flow 45 back and forth through the pipes. The interior of the heat exchanger is provided with a baffle 60 above the pipes 21. This baffle is provided with spaced openings 60a therein and is used to distribute the steam evenly throughout the 50 length of the heat exchanger.

55 Liquid to be heated is conveyed through a pipe 24 into the intake of the first centrifugal pump 11. The outlet of the pump communicates 60 through a pipe 25 to the inlet of the heat exchanger 10. The outlet of the heat exchanger

is connected by a pipe 26 to a cross-pipe 27 having four branches. The pipe 26 communicates with one branch of the cross-pipe while a second branch serves as a product outlet through a hand operated valve 28. A third branch has the thermostatically operated temperature control pilot valve 15 mounted thereon and the fourth branch communicates through a spring operated relief valve 29 to a pipe 30 extending to the product intake pipe 24. This last branch, relief valve 29 and pipe 30 are used for recirculating the product through the pump 11.

The thermostatically operated pilot valve 15 is connected through a line 31 to a source of air under pressure. A second line 32 extends from the pilot valve 15 to a reverse-acting steam supply valve 14. The pilot valve 15 controls the amount of steam that is admitted through the steam supply line 12 to the heat exchanger 10. As was described in the above-mentioned copending application Serial No. 737,676, now Patent No. 2,533,141, the pilot valve 15 is used as a temperature controller and is provided with a thermostat bulb extending into the cross-pipe 27 so that it is in contact with the heated liquid flowing from the heat exchanger. When the heated liquid reaches a temperature greater than a predetermined temperature, a relief port in the pilot valve 15 is opened and the air supply from line 31 and pressure within line 32 is vented to atmosphere, thereby relieving pressure on the diaphragm in the valve 14 and permitting the spring 14a to close the valve. When the temperature of the heated liquid is below the predetermined temperature, the pilot valve 15 will close the vent and permit air under pressure to flow through the line 32 and act on the diaphragm to open valve 14. When this is done, the spring 14a on the supply valve 14 is compressed. This arrangement is described and claimed in my aforementioned copending application.

The adjustable spring pressure relief valve 29 is used to permit any desired amount of recirculation of the liquid and is controlled by the spring tension and the amount that valve 29 is opened. The spring pressure can be varied to provide any desired pressure on the product flowing through the valve 28 and the outlet 33.

When the valve 28 is closed, however, the heated liquid will force the relief valve 29 open and permit the liquid to flow through pipe 30 and pipe 24 into the intake of the pump 11. Thus, so long as valve 28 is closed, or at least partially closed, the liquid will be recirculated through the heat exchanger 10. As the temperature in the heat exchanger is controlled by the pilot valve 15, there is no danger of the liquid becoming overheated during this recirculation. This means for recirculating the liquid product through the heat exchanger is also described and claimed in my copending application, Serial No. 737,676, now Patent No. 2,533,141.

One of the important features of the present invention is the improved means for removing condensate from the heat exchanger 10. This means comprises a steam condensate chamber 16 located at the bottom of the heat exchanger 10 and communicating therewith through a relatively large opening 16b. The bottom of the condensate chamber is connected through a pipe 34 and a pipe 35 to the intake of a centrifugal pump 17. The outlet of the pump 17 is connected through pipes 61 and 36 to a Venturi ejector 19. This Venturi ejector is of a standard type and is connected through a pipe 37 to the interior of

the condensate chamber 16 at a point above the highest level of the condensate 16b in the chamber. With this arrangement the Venturi ejector 19 creates a vacuum and draws non-condensable gases through the pipe 37 and mixes them with the condensate being forced through the Venturi ejector. The ejector 19 is surrounded by a cylindrical housing 20 having its top provided with a gas outlet line 38. The Venturi ejector 19 is arranged vertically in the housing 20 and discharges against a baffle 20a located in front of the inlet on the line 38 so that the condensate will not be forced into the gas line. The gas outlet line 38 leads to a gas escape chamber 39 having an opening 39a in the top thereof through which the gas can escape into a discharge line 40. The gas escape chamber 39 is provided with a float 41 having an upstanding stem 41a held in position by a guide means 42 so that it is aligned with the opening 39a. This float and stem is provided so that if condensate should flow through the gas outlet line 38 into the chamber 39, the buoyancy of the float 41 would cause it to rise and close the opening 39a and thus prevent the escape of condensate out the opening 39a. Any condensate that enters the gas line 38 is returned to the bottom of the housing 20 by means of a return line 43.

The bottom of the housing 20 is connected through a pipe 44, a spring pressure relief valve 45 and a pipe 35 to the intake of the centrifugal pump 17.

The condensate outlet pipe 61 from the pump 17 is connected through a pipe 46 to the float operated valve 18. The other side of the float operated valve is connected to a check valve 47 which permits flow of condensate in a direction away from the valve 18 but not towards it.

The float operated valve 18 is located in an extension 16a of the condensate chamber 16. Access to the valve is provided by a lower pipe section 53 attached to pipe 46 and extending through the condensate chamber extension 16a. A similar pipe 54 extends through the upper part of the condensate chamber 16 and provides access to the upper part of the valve. This pipe 54 is connected to the check valve 47. Each of the pipes 53 and 54 is sealed by means of a packing 55 therearound with each packing being held compressed against its pipe by means of a threaded compression collar 56. With this arrangement the condensate discharge is confined within the body of the valve 18 and cannot enter the chamber 16. This arrangement also permits free play of the arm on the float 48.

The valve 18 is operated by a float 48 located within the condensate chamber 16. The float 48 and valve 18 are so arranged that when the float rises the valve is opened and when the float falls the valve is closed. With this arrangement a substantially constant level of condensate is maintained in the chamber 16 and thus a substantially constant head is maintained on the centrifugal pump 17. The pressure within the casing of the pump 17, pipe 61 and pipe 46 is maintained constant, thereby permitting the pump to discharge condensate at a constant rate under variable temperatures and pressures within the chamber 16.

In order that condensate flowing from the heat exchanger 10 along the bottom thereof and then through the opening 16b into the condensate chamber 16 will not cascade onto the float 48 and affect its operation, there is provided a substantially circular baffle 49 having the shape of

the frustum of a hollow cone. This baffle is spaced inwardly from the side of the opening 10b and has its top extending above the opening and its bottom extending below the opening. The baffle is held in place by spaced retaining means (not shown) so that flow of condensate between the baffle and the opening 10b is unimpeded. With this arrangement, condensate flowing from the bottom of the exchanger 10 and cascading through the opening 10b will strike the baffle 49 and be directed onto the walls of the condensate chamber 16 so that the condensate will not strike the float 48 except for the small amount that condenses on the pipes 21 above the baffle 49 and drops directly through the open top of the baffle 49 onto the float 48. This small amount does not materially affect the operation of the float. The end of the pipe 37 which is used to convey non-condensable gases from the heat exchanger is located immediately beneath the baffle 49 so that this end of the pipe is also protected by the baffle.

In the operation of the condensate removal means, the float operated valve 18 will be maintained closed until the condensate 16b in the condensate chamber 16 reaches a predetermined level. While this valve is closed, condensate is withdrawn through pipes 34 and 35 into the intake of the centrifugal pump 17. The condensate is then ejected from the pump through pipes 61 and 36 into the Venturi ejector 19. The Venturi ejector draws non-condensable gases from the heat exchanger through the pipe 31 and ejects the mixed gases and condensate against the baffle 20a in the housing 20. The non-condensable gases rise to the top of the housing 20 and escape through the gas outlet line 38, chamber 39, opening 39a and line 40. The housing 20 is substantially filled with condensate at all times so that the Venturi ejector remains submerged. Any condensate flowing into the gas outlet line 38 will be returned by line 43 to the bottom of the housing 20. Escape of this condensate through the opening 39a will be prevented by operation of the float 41 and stem 41a. In normal practice, the gas escape chamber 39 will be substantially filled at all times with non-condensable gas under pressure greater than atmosphere due to the resistance of the spring pressure relief valve 45. When all gases in chamber 39 have escaped, condensate enters the chamber 39 and raises float 41 to close opening 39a and prevent the escape of condensate. The condensate in housing 20 that surrounds the Venturi ejector 19 is necessarily recirculated through pipe 44 and pipe 35 back to the intake of the pump where it is again ejected from the pump through pipe 61 and pipe 36, and thus back through the ejector 19 and again into the housing 20. This recirculation is necessary because when the float-operated valve 18 is closed, as shown in Fig. 2, no condensate can be forced out pipe 46 and no further condensate is withdrawn through pipe 34 from the condensate chamber 16. Thus when the valve 18 is closed, as shown, the condensate is circulated in this described closed path.

By interposing spring-loaded relief valve 45 at the joinder of pipes 44 and 35, the condensate in housing 20 is always maintained at a predetermined pressure depending upon the spring setting of valve 45, which, as is shown in the drawing, is adjustable. With the valve 45 positioned as shown, no condensate can recirculate back to the pump from the housing 20 through

pipes 44 and 35 until the pressure of the spring of the valve 45 has been overcome. As in the closed system shown this recirculation is achieved, the condensate within housing 20 is always maintained under a pressure approximately equal to the setting of the relief valve 45 as otherwise no condensate could flow from housing 20 through the relief valve 45 and this flow is forcibly achieved because of the above described closed system.

As the pressure of the condensate in housing 20 is maintained at a predetermined super-atmospheric pressure because of the loading of the spring in the relief valve 45, the non-condensable gases in the gas escape chamber 39 are also maintained at this super-atmospheric pressure as the gases flow out the opening 39a. This opening being restricted, as shown in the drawings, causes a relatively slow flow of the gases. If the non-condensable gases do become completely forced out of chamber 39 so that the condensate under pressure rises in this chamber, very little or no condensate will be forced from the gas escape line 40 because of the float 41 rising in chamber 39 so that the stem 41a of the float will close the restricted opening 39a. As the pressure on the condensate in housing 20 is maintained at super-atmospheric pressure because of the loading of the spring and relief valve 45, for the reasons explained above, this pressure will be sufficient to force a portion of the condensate from housing 20 through pipe 50 into the steam supply line 21 to desuperheat the steam.

When the level of condensate in the condensate chamber 16 becomes greater than the predetermined level, the float 48 rises and opens the float operated valve 18. When this valve is opened, condensate is forced by the pump 17 through the pipes 61 and 46, float operated valve 18 and check valve 47 into a sewer or condensate system at full pump pressure. This causes the level of condensate in the chamber 16 to fall and thus lowers the float 48 until the valve 18 is again closed. During this cycle of operation, a portion of the condensate is being recirculated through the pump 17 while another portion is used to de-superheat the steam supply as has been previously described.

In one embodiment of the invention, low pressure steam is used for heating the heat exchanger. This steam, in one embodiment, is from 5.5 to 30 pounds absolute pressure, although it is obvious that other pressures may be used. With steam supplied within the range of 5.5 to 30 pounds per square inch absolute, the liquid to be heated may easily be maintained at a temperature between 90 and 220° F. without requiring the liquid to remain for too great a time in the heater. The product may be heated to any desired temperature, however, by merely adjusting the thermostatically operated pilot valve 15. When it is desired to heat the product to a higher temperature, it will be advisable to employ steam at correspondingly higher pressures. The range of 5.5 to 30 pounds steam pressure is desirable when heating sensitive liquids such as milk, fruit juices and the like. Within this range, it is easier to prevent scorching, precipitating the solids, destruction of food value and the like.

In some embodiments of the invention, the condensate within the housing 20 is maintained at from 5 to 12 pounds per square inch gauge pressure by the action of the relief valve 45. This pressure serves to force the non-condensable gases through the opening 39a and to force a

portion of the condensate through the line 50 into the steam supply line 12 and de-superheat the steam. It is preferred that the condensate pressure in the housing 20 be kept as low as possible as the efficiency of the Venturi ejector is inversely proportional to the pressure of the condensate in which the ejector is submerged.

When the heat exchanger is first placed in operation, the steam pressures and temperatures are higher than normal while the apparatus is reaching equilibrium. For this reason, the condensate that accumulates in the condensate chamber 16 is at a higher temperature than is normally encountered. As the system reaches equilibrium and the temperature within the heat exchanger becomes lower, the accumulated condensate releases some of its heat in vapor form so that it can be used in heating the liquid product. Because of the relatively large size of the opening 10b, this vapor can return to the heat exchanger without interfering with the flow of the condensate into the condensate chamber 16 from the heat exchanger. There is also a secondary source of vapor from the condensate chamber 16 due to the mechanical energy transmitted to the condensate by the recirculation of a portion of the condensate. This mechanical energy is therefore also used to supply additional heat to the heat exchanger.

The heat exchanger shown in the accompanying drawings employs an improved type of gasket for sealing each of the headers 22 and 23 in place. As shown in Fig. 3, the header 22 is provided with a flange 22a provided on the inner surface thereof and adapted to have a metal-to-metal contact with the end 10c of the heat exchanger 10. The header is also provided with a partition 22b also having a metal-to-metal contact with the end 10c of the heat exchanger so as to direct the flow of liquid through the proper tubes. The header is provided with spaced bolts 51 arranged an appreciable distance from the flange 22a. Between these bolts 51 and flange 22a there is located a paper gasket 52 having its inner periphery bearing against the flange 22a and its outer periphery bearing against the bolts 51. This paper gasket serves to seal the header and is disposable so that it may be thrown away and replaced by a new one whenever a header is removed for cleaning the heat exchanger, making repairs or the like. The gasket prevents leakage between the flange 22a and the end member or header sheet 10c. This gasket is preferably made from sterile, sanitary milk cap paper stock or paper of similar quality and preferably has a width not less than about fifteen times its thickness. In a typical embodiment, it was 0.035 inch thick. The gasket is not perforated as the outer periphery thereof merely bears against the bolts 51. If desired, however, it may bear against a ring structure or the like. As the gasket is unperforated, it has considerable strength to resist the internal pressures. It is preferred that the gasket be somewhat thicker than the length of the flange 22a so that when the bolts 51 are tightened, the gasket will be compressed. In the embodiment where the gasket was 0.035 inch thick, it was compressed to a thickness of 0.028 inch when in use. The use of this improved gasket eliminates the hazards due to blowing of regular conventional rubber and rubber base gaskets, avoids gasket flow due to high temperatures and pressures, reduces the cost of the gaskets, permits assembly of the headers and gaskets easily and accurately and are sanitary. No

gasket is needed under the partition 22b as the pressures on opposite sides of this partition 22b are substantially equal. The contacting surfaces of the flange 22a and partition 22b and the header plate 10c should be carefully machined so that an efficient metal-to-metal contact is provided.

The other header 23 is similarly provided with a flange 23a, partitions 23b and gasket 52.

The foregoing detailed description is given for clearness of understanding only, and no unnecessary limitations should be understood therefrom, for some modifications will be obvious to those skilled in the art.

I claim:

1. In a heating system for liquids wherein the liquid is heated by passing it through a steam chamber, means for removing condensate from said steam chamber comprising a condensate chamber communicating with the steam chamber, a centrifugal pump having its intake communicating with the condensate chamber, an outlet conduit from said pump, a Venturi ejector communicating with said outlet conduit, a casing surrounding the Venturi ejector, a gas outlet line in the top thereof, a conduit extending from the Venturi ejector to the condensate chamber at a point above the normal condensate level therein for the removal of non-condensable gases, valve means in said gas outlet line for preventing the escape of condensate therethrough, and means for maintaining a predetermined amount of condensate in said casing.

2. The heating system of claim 1 wherein said Venturi ejector discharges upwardly and a baffle is provided between the outlet end of the ejector and said gas outlet line for preventing the direct discharge of condensate into said outlet line.

3. The heating system of claim 1 wherein there is provided a conduit extending between the gas outlet line and the bottom of said casing for returning condensate entrapped in gas flowing through said line.

4. The heating system of claim 1 wherein said gas outlet line and valve means comprises a gas chamber having an opening in the top thereof and a float operated valve in the gas chamber arranged to close said opening when condensate fills said gas chamber, and there is provided a conduit extending between the gas chamber and the bottom of said casing for returning condensate entrapped in gas flowing through said gas chamber.

5. The heating system of claim 1 wherein said means for maintaining condensate in said casing comprises a condensate conduit extending from said casing to the inlet of said centrifugal pump and a relief valve in said conduit arranged to open at a predetermined pressure.

6. In a heating system for liquids wherein the liquid is heated by passing it through a steam chamber, means for removing condensate from said steam chamber comprising a condensate chamber communicating with the steam chamber, a centrifugal pump having its intake communicating with the condensate chamber, an outlet conduit from said pump, a Venturi ejector communicating with said outlet conduit and discharging upwardly, a casing surrounding the Venturi ejector, a gas outlet line in the top thereof, a baffle between the outlet end of the ejector and said gas outlet line for preventing the direct discharge of condensate into said outlet line, a conduit extending from the Venturi ejector to the condensate chamber at a point above the normal condensate level therein for the removal

of non-condensable gases, a gas chamber having an opening in the top thereof and a float operated valve in the gas chamber arranged to close said opening when condensate fills said gas chamber, a conduit extending between the gas chamber and the bottom of said casing for returning condensate entrapped in gas flowing through said gas chamber, and means for maintaining condensate in said casing comprising a condensate conduit extending from said casing to the inlet of said centrifugal pump and a relief valve in said conduit arranged to open at a predetermined pressure.

7. The heating system of claim 6 wherein there is provided a condensate line extending from said condensate conduit on the portion thereof between the casing and the pressure relief valve to the steam inlet of said steam chamber for de-superheating the steam.

8. In a heating system for liquids wherein the liquid is heated by passing it through a steam chamber, means for removing condensate from said steam chamber comprising a condensate chamber communicating with the steam chamber for collecting condensate, a centrifugal pump having its intake communicating with the condensate chamber, an outlet conduit from said pump, a valve in said conduit, a float in the condensate chamber operatively connected to the valve to open the valve when the float rises and close the valve when the float falls, a second outlet conduit communicating with the outlet from said pump, a Venturi ejector on said second outlet conduit through which condensate is forced by said pump, a gas conduit extending from the Venturi ejector to the condensate chamber at a point above the normal condensate level therein for the removal of non-condensable gases, said gases being entrapped in the condensate flowing through the Venturi ejector, a casing into which the Venturi ejector ejects condensate, and means for returning at least a portion of the condensate from the Venturi ejector to the intake of the centrifugal pump to provide for recirculation of condensate through the pump, Venturi ejector, casing, and back to the pump.

9. In a heating system for liquids wherein the liquid is heated by passing it through a steam chamber, means for removing condensate from said steam chamber comprising a condensate chamber communicating with the steam chamber for collecting condensate, a centrifugal pump having its intake communicating with the condensate chamber, an outlet conduit from said pump, a valve in said conduit, a float in the condensate chamber operatively connected to the valve to open the valve when the float rises and close the valve when the float falls, a second outlet conduit communicating with the outlet from said pump, a Venturi ejector on said second outlet conduit through which condensate is forced by said pump, a gas conduit extending from the Venturi ejector to the condensate chamber at a point above the normal condensate level therein for the removal of non-condensable gases, said gases being entrapped in the condensate flowing through the Venturi ejector, a casing surrounding the Venturi ejector, a gas outlet line in the top thereof, a conduit extending from the Venturi ejector to the condensate chamber at a point above the normal condensate level therein for the removal of non-condensable gases, valve means in said gas outlet line for preventing the escape of condensate therethrough, and means for main-

taining a predetermined amount of condensate in said casing.

10. In a heating system for liquids wherein the liquid is heated by passing it through a steam chamber, means for removing condensate from said steam chamber comprising a condensate chamber communicating with the steam chamber for collecting condensate, a centrifugal pump having its intake communicating with the condensate chamber, an outlet conduit from said pump, a valve in said conduit, a float in the condensate chamber operatively connected to the valve to open the valve when the float rises and close the valve when the float falls, a second outlet conduit communicating with the outlet from said pump, a Venturi ejector communicating with said outlet conduit and discharging upwardly, a casing surrounding the Venturi ejector, a gas outlet line in the top thereof, a baffle between the outlet end of the ejector and said gas outlet line for preventing the direct discharge of condensate into said outlet line, a conduit extending from the Venturi ejector to the condensate chamber at a point above the normal condensate level therein for the removal of non-condensable gases, a gas chamber having an opening in the top thereof and a float operated valve in the gas chamber arranged to close said opening when condensate fills said gas chamber, a conduit ex-

30 tending between the gas chamber and the bottom of said casing for returning condensate entrapped in gas flowing through said gas chamber, and means for maintaining condensate in said casing comprising a condensate conduit extending from

35 said casing to the inlet of said centrifugal pump and a relief valve in said conduit arranged to open at a predetermined pressure.

11. In a heating system for liquid wherein the liquid is heated by passing it through a steam chamber, means for removing condensate from said steam chamber comprising a condensate chamber communicating with the steam chamber for collecting condensate, a centrifugal pump having its intake communicating with the condensate chamber, an outlet conduit from said pump, means for recirculating at least a portion of the condensate from the outlet conduit through said pump, a Venturi ejector also in said recirculating system communicating with the outlet of said pump, means for maintaining said ejector normally submerged in a portion of the condensate, means for forcing another portion of the condensate through said ejector for creating a vacuum therein, and gas conduit means extending between the vacuum creating portion of said ejector and the steam chamber for removing non-condensable gases therefrom.
